UNITED STATES PATENT OFFICE.

WARREN F. STANTON, OF PAWTUCKET, RHODE ISLAND, ASSIGNOR TO MATIE C. MESSLER, OF PAWTUCKET, RHODE ISLAND.

COMPRESSION-OPERATED IGNITION DEVICE.

1,279,473.

Specification of Letters Patent. Patented Sept. 17, 1918.

Application filed November 9, 1916. Serial No. 130,332.

To all whom it may concern:

Be it known that I, WARREN F. STANTON, a citizen of the United States, residing at Pawtucket, in the county of Pawtucket and State of Rhode Island, have invented certain new and useful Improvements in Compression - Operated Ignition Devices, of which the following is a specification.

My invention relates to compression operated ignition devices adapted for internal combustion engines, pumps and other devices.

The essential object of my invention is to produce a compression operated ignition device that is effective in operation upon engines and power mechanisms of low speed. Further objects, are to insure, in such ignition devices applied to low speed mechanisms, an effective spark at a minimum rate of compression, as well as sparks of uniform intensity, and correctly timed, and capable of adjustable timing.

The invention consists in employing the compressed charge solely to store up energy in the impelling spring by the outward piston stroke, and in relying exclusively upon said impelling spring to generate the current and to open the circuit, so that the piston is entirely free of the generating member during the current generating and circuit breaking period. Other novel features will hereinafter appear and will form the subject matter of claims hereto appended.

In the accompanying drawings which form a part of this specification—

Figures 1 and 2 are plan and side elevations respectively of my device, showing the adjacent portion of an engine cylinder in section,

Fig. 3, a section on line 3—3 of Fig. 2,

Fig. 4, a partial section on line 4—4 of Fig. 3,

Fig. 5, a bottom plan view of a portion of my device,

Fig. 6, a transverse section of the device on line 6—6 of Fig. 3,

Fig. 7, a rear elevation of the device,

Fig. 8, a section on line 8—8 of Fig. 2,

Fig. 9, a section of the device corresponding to the section shown in Fig. 3, but showing the operative parts in another position, and

Fig. 10, a section on line 10—10 of Fig. 9.

Similar reference numerals indicate similar parts throughout the views.

In the drawings 13 is the cylinder wall, and 14 the combustion chamber of an internal combustion engine in which my device in the present instance is shown to be mounted. The plug portion 16 of my igniter is located in an opening 17 in the cylinder wall, and a flange 18 thereon is attached to the wall by bolts 19 entering threaded cavities 20.

A bracket arm 22 has an attaching plate 23 engaged by screws 24 to the flange 18, and is integral with the magneto casing 26 comprising a hollow upper portion 27 with an open top covered by a plate 29 attached by screws 31. The casing portion 27 has opposite horizontal extensions 33 and 34. The extension 33 has a bore 35 extending to a piston chamber 36 extending through the plug; within which bore is a bushing sleeve 38. In the chamber 36 is a piston 40 whose end face is exposed in the chamber 14. The piston rod in this case comprises a section 42 rigid with the piston and a section 43 connected to the first by a joint as at 45. The piston rod or section 43 extends through the bushing 38, across the casing portion 27 and into the extension 34, and is slidably in an extended portion 47 of the latter provided with external threads 48. These threads engage threads 50 in one end of a barrel 51. The portion 47 is of less internal diameter than that of the barrel 51, whereby there is formed an internal stop shoulder 53 in the path of a plate 54 fixed by a screw 55 or otherwise to the end of the piston rod. This plate, which is of greater diameter than the rod, may be integral with the latter. An internally threaded milled cap 56 is removably engaged with the externally threaded end of the tube 51 and has bearing against its inner face one end of a helical spring 59 whose other end bears against the end of the piston or the plate 54. This cap operates on the spring as an adjustment, whereby the outward movement of the piston is delayed until the pressure in the cylinder is increased, thus retarding the spark.

The extension 33 has also a passage 60 parallel with the bore 35; and there is a passage 61 in alignment therewith in the plug. In these two passages is an axially

movable electrode 63 having a contact finger 64 on its end within the chamber 14. Upon its opposite end is fixed a collar 66 provided with a lateral longitudinally extending finger 68, but the collar and finger may form an integral part of the electrode. A spring 69 has one end attached to a pin 70 in the collar, and its other end 72 engaging the casing through a hole 73 in the latter. Another electrode 74 fast in the plug, is insulated therefrom by a sleeve 75, and extends into the chamber 14, having a lateral projection 76 in the path of the finger 64. On the other end of the electrode is a binding post 78.

The magneto or generator comprises the casing 26 carrying the magnets 80, and the armature shaft 81 journaled in upper and lower bearings 82 and 83. Fast on the upper end of the shaft is fixed a crank disk or arm 84 carrying a crank pin 85 which is in the path of a flange 87 on the piston section 43, but out of the path of a stop shoulder 88 on the latter. The front face of the shoulder 87 is plane, and the rear face is frusto conical forming a longitudinally disposed curved recess in the piston 43. The shoulder 88 merely limits the outward travel of the piston. The pin 85 is also adapted to contact with a cam surface 90 on the bottom of the finger 68. The frame 26 of the magneto includes a bottom plate 91 integral with the bearing 83. Near the end of this plate is a post 93 through which passes an adjusting screw 94 upon which is a thumb nut 95. Fast to one downwardly projecting end of the armature shaft is a crank arm 97 carrying a crank pin 98 to which is fixed one end of a spring 99 whose other end engages the screw 94. The crank arm 97 is axially adjustable on its shaft by a binding screw 100. The armature winding 101 of the magneto has one terminal 102 grounded in the armature shaft, and its other terminal 103 passes through an opening 104 into a central longitudinal passage 105 in the upper end of the armature shaft, and is insulated therefrom by material 106, and is connected to a binding post 107, from which extends the wire 108 passing through an opening 109 in the casing to the binding post 78.

The operation of my device is as follows: The compressed engine charge in the chamber 14 outwardly moves the piston 40, piston rod 43, and flange 87, which are normally positioned as shown in Fig. 3, whereby the flange in its outward movement moves the crank pin 85 and its arm or disk 84 in the direction of the arrow in said figure, thus increasing the tension of the spring 99 or storing up energy therein. When the parts have reached the point shown in Fig. 9 the pin 85 is released by the flange which slides over the same. At the instant of release the pin oscillates in the opposite direction

as shown by the arrow in the latter figure, being impelled wholly by the stored up energy of spring 99 and at greater speed than that of the piston, and strikes the bevelled or cam surface 90 of the member 68, thus moving the finger 64 of the electrode 63 to break the circuit and produce a spark to ignite the compressed charge. The spring 59 returns the rod 43 and flange 87 to original position. In its return the flange, while contacting with the pin, merely presses the latter out of the way without difficulty as the spring 99 permits the pin to yield. The spring 69 returns the finger 68 to original depressed position in the path of the pin.

A second means for timing the spark and adapting the device to varying compressions within the cylinder is the nut 95 operating on the screw 94 to vary the tension on spring 99.

I claim:

1. In a compression operated ignition device, the combination with the current generating member and the circuit, of an oscillatory crank member on the generating member adapted by its current generating movement to break the circuit, a spring connected to the generating member for actuating the crank member, and a piston actuated by the engine charge movable independently of the generating member slidably engaging and retracting the crank member.

2. In a compression operated ignition device, the combination with the current generating member and the circuit, of an oscillatory crank member on the generating member adapted by its advance inward or current generating movement to break the circuit, a spring connected to the generating member for imparting said movement to the crank member, and means, a piston movable independently of the generating member and actuated by the engine charge for retracting the crank member and for releasing the same after said retraction.

3. In a compression operated ignition device, the combination with the current generating member and the circuit, of an oscillatory crank member on the generating member adapted by its vibration to intermittently break the circuit, a spring attached to the generating member for moving the crank member in one direction of its vibration, and a piston actuated by the engine charge intermittently engaging the crank member to move the crank member in the opposite direction of its vibration.

4. In a compression operated ignition device, the combination with the current generating member and the circuit, of an oscillatory crank member on the generating member adapted in one direction of its vibration to break the circuit, a spring connected with the generating member for impelling the crank member in the direction to break

the circuit, and a piston actuated by the compressed engine charge slidably engaging the crank member and moving the same in the opposite direction and then releasing the 5 crank member.

5. In a compression operated ignition device, the combination with the armature and the circuit, of an oscillatory crank member fast on the armature adapted in its inward 10 movement to break the circuit, a spring engaging the armature for inwardly moving the crank member, a piston rod outwardly impelled by the engine charge, and a projection on the rod adapted to engage and over- 15 ride the crank member during the outward stroke of the piston rod.

6. In a compression operated ignition device, the combination with the piston, piston rod, stationary electrode and movable 20 electrode, of means for vibrating the piston, and axially movable armature, a crank arm on the armature, a pin on the arm, a cam projection on the movable electrode in the path of the pin, yielding means for moving 25 the armature in one direction, and a projection on the piston non-engageable with the cam and engageable with the pin for moving the armature in the opposite direction.

7. In a compression operated ignition device, the combination with the piston and piston rod, of a spring engaging the rod to return the piston, a projection on the piston, an axially movable armature, a crank member on the armature engageable by the projection during a portion only of the outward travel of the piston, and means on the armature for inwardly impelling the crank member at a greater speed than the speed of the returning piston.

40 8. In a compression operated ignition device, the combination with the piston actuated by the engine charge and the piston rod, of a spring in alignment with the piston and engaging the rod to return the piston, 45 a projection on the piston rod, a circuit, an axially movable armature, a crank member on the armature in the path of the projection, and a spring for moving the crank member independently of the piston rod.

50 9. In a compression operated ignition device, the combination with the piston and piston rod, of a spring in alignment with the piston and in contact with the piston rod, a projection on the piston rod, means for adjusting the tension of the spring, a circuit, 55 an axially movable armature, a crank member on the armature free of the projection but in the path of said projection, and yielding means on the armature for impelling the 60 crank member after the release of the crank member by the projection.

10. In a compression operated ignition device, the combination with the current generating member and the circuit, of an oscillatory crank member on the generating member adapted in its inward generating movement to break the circuit, a spring connected to the generating member for imparting inward movement to the crank member, means for adjusting the length of the spring, 70 and a piston movable independently of the generating member and actuated by the engine charge for outwardly retracting the crank member and for releasing the crank member after said retraction. 75

11. In a compression operated ignition device, the combination with a frame, of a vertically disposed oscillatory armature in the frame, a circuit, a spring for oscillating the armature inwardly to generate a current, a piston mounted in the frame at right angles to the armature and actuated by the engine charge, a projection on the piston, and a crank member fast to the armature in the path of the projection during the outward 85 stroke of the piston, and free of the projection during the inward oscillation of the armature.

12. In a compression operated ignition device, the combination with the frame, of a vibratory electrode in the frame, an oscillatory armature in the frame, a piston in the frame actuated by the engine charge, a projection on the piston, an arm on the armature, a pin on the arm engaged and released 90 by said projection during the outward stroke of the piston, and resilient means for forcing the pin into operative contact with the electrode after the release of the pin by the projection. 100

13. In a compression operated ignition device, the combination with the frame, of an oscillatory armature in the frame, a crank arm upon one end of the armature, a spring connecting the crank arm to an adjacent part of the frame, an arm on the other end of the armature, a pin on the second arm, a piston in the frame actuated by the engine charge, a spring for returning the piston, and an annular projection upon the piston 105 provided with a plane formed face adapted to engage and release the pin during the outward stroke of the piston, and provided with a frusto conical rear face adapted to engage and override the pin during the return movement of the piston. 110 115

In testimony whereof I have affixed my signature in presence of two witnesses.

WARREN F. STANTON.
